UNITED STATES PATENT OFFICE

164,254

POSTING MACHINE

Saul Nathan, Chicago, Ill.

Application June 15, 1948, Serial No. 146,970

Term of patent 3½ years

(Cl. D64—11)

To all whom it may concern:

Be it known that I, Saul Nathan, a citizen of the United States and a resident of Chicago, Cook County, Illinois, have invented a new, original, and ornamental Design for a Posting Machine, of which the following is a specification, reference being had to the accompanying drawing, forming a part thereof.

Fig. 1 is a front perspective view of a posting machine, showing my new design.

Fig. 2 is a rear perspective view of the same.

I claim:

The ornamental design for a posting machine, substantially as shown.

SAUL NATHAN.
